UNITED STATES PATENT OFFICE.

GUSTAV EGLOFF AND HARRY P. BENNER, OF CHICAGO, ILLINOIS, ASSIGNORS TO UNIVERSAL OIL PRODUCTS COMPANY, OF CHICAGO, ILLINOIS, A CORPORATION OF SOUTH DAKOTA.

DEPHLEGMATOR.

Application filed May 2, 1921, Serial No. 466,173. Renewed September 10, 1925.

To all whom it may concern:

Be it known that we, GUSTAV EGLOFF and HARRY P. BENNER, both citizens of the United States, residing in the city of Chicago, county of Cook, and State of Illinois, have invented certain new and useful Improvements in Dephlegmators, of which the following is a specification.

This invention relates to dephlegmators and refers more particularly to a sectional dephlegmator which has a number of removable stages adapted to be interchanged and adjusted in a manner that the quality of vapors and the character of the distillate is readily controlled.

Among the salient objects of the invention are to provide an apparatus comprising a dephlegmator having a series of successive stages divided therein by means of shelf-like perforated plates through which the vapors are directed in their travel through the dephlegmator; to provide a dephlegmator or rectifier in which the plates are not only removable but are built up in sections so that the porosity of the individual plates or dividing partitions between the zones may be regulated by inserting sections having a greater or less number of apertures therethrough; thereby facilitating or obstructing the passage of the vapors through the length of the condenser; to provide an apparatus which permits the drawing off of distillate from the different zones which increases the capacity as there is no substantial accumulation of liquid condensate in the structure; to provide a dephlegmator that may be readily cleaned and one that is positive in operation.

In the drawings:

40 Fig. 1 is a side elevational view of an oil cracking apparatus having the dephlegmator mounted above the expansion chamber.

Fig. 2 is an enlarged sectional view of the dephlegmator.

45 Fig. 3 is a detail of the means for positioning the partition plates on the central shaft.

Fig. 4 is a plan view of one of the skeleton frames for supporting the partition shell.

50 Fig. 5 is a face view of one of the uppermost partition plates.

Fig. 6 is a face view of one of the lower partitions showing the increased number of apertures therein.

Referring particularly to the drawings, 55 describing briefly the use of the dephlegmator in connection with the oil cracking apparatus shown, the raw oil is introduced from any suitable source through the inlet line 1, controlled by a valve 2 and is charged 60 to the heating tubes 3 mounted in the furnace 4 by means of the charging pump 5 and a charging line 6 regulated by a valve 7. The oil, after being heated to a cracking 65 temperature in the heating tubes is directed through the transfer line 8 to the expansion chamber 9 to which zone the vaporization is restricted. The vapors released from the oil rise to the dephlegmator 10 while the 70 heavier residual liquid is drawn off through residuum line 11, controlled by a valve 12 and directed to storage or to other desired means for treatment. The dephlegmator 10 comprises an outer shell 13 which is closed 75 at both ends by means of closure caps 14. To the upper closure member is fastened a 80 shaft or rod 15 extending down through the center of the dephlegmator. This central shaft is drilled or notched as shown at 16 to accommodate the set screws 17, which serve 85 to hold the spiders 18. These spiders are nothing more than skeleton frames such as shown in Fig. 4 for supporting the plates 19, which when laid side by side, are built up to form the partition shelves in the dephleg- 90 mator. The lower shelves or partitions have a greater number of apertures 20 in the plates as shown in Fig. 6, while the uppermost partitions are similar to those shown in Fig. 5, where the number of apertures or 95 holes through the partitions are greatly decreased. Besides the controlling of the speed and volume of the vapors which pass up to the dephlegmator, by means of the number of apertures in the plates, an additional control may be had by the positioning of the plates at predetermined intervals on the shaft, by means of the set screws 17, which are adapted to set into the notches 16 in the shaft. The dephlegmator has also 100 two removable clean out plates 21, and liquid drawoff lines 22, controlled by valves 23 spaced at intervals throughout its length.

Vapors generated in the vaporizing chamber rise into the lower part of the dephlegmator and pass through the apertures in the plates positioned at intervals throughout the 105 length of the dephlegmator, the condensate

being drawn off through the lines 22, which communicate with a vertical drawoff line 24 connecting with the lower drawoff 25 controlled by a valve 26. The lower drawoff 5 leads to a water condenser 27 from which the condensed distillate is collected in a receiver 28 which is equipped with a liquid drawoff line 29 controlled by a valve 30 and a pressure relief pipe 31 regulated by a valve 10 32. In operating a cracking system with the above described dephlegmator, it is understood that with different types of oil and under different conditions of treatment, the positioning of the partitions in the dephlegmator and the number of partitions used, besides the type of partition will vary. In some cases, where a large volume of vapors are to be treated, it may be necessary to use the baffle plates having a large number of 20 apertures throughout the length of the dephlegmator and in other cases, the perforated baffles with the large number of apertures will only be used in the lower portion of the dephlegmator. In addition to the 25 control, the character of the baffles, and positioning of the baffles is of importance.

We claim as our invention:

1. A dephlegmator for an oil cracking system, comprising a chamber having vapor inlet and outlet, ports and a plurality of baffle partitions dividing the chamber into stages adapted to obstruct the travel of the vapors, means for drawing off the condensate at various stages in the vapors' travel, 35 the position of said baffles relative to one another being manually variable, and adjustable means for holding said baffles in their different positions of adjustment.
2. A dephlegmator, comprising a casing 40 having a vapor inlet and a vapor outlet, a central standard disposed within said casing, a plurality of perforated plates mounted on said standard adapted to obstruct the travel of vapors through the dephlegmator, and 45 manually adjustable means connected with each plate for maintaining the plates in

different positions of adjustment relative to one another.

3. A dephlegmator, comprising a casing having a vapor inlet and a vapor outlet, a 50 central standard disposed within said casing, a plurality of perforated plates mounted on said standard adapted to obstruct the travel of vapors through the dephlegmator, and manually adjustable means connected with 55 each plate for maintaining the plates in different positions of adjustment relative to one another, said means including a collar and a retaining pin threaded therein for each baffle, in combination with a plurality of 60 sockets in said standard disposed in spaced relation and adapted to receive said retaining pins.

4. A dephlegmator comprising a casing and central standard disposed therein, a 65 plurality of partitions in said casing, and means for adjustably supporting said partitions on said standard whereby the positions thereon may be manually varied, said means including an adjustable element 70 connected with each partition and adapted to cooperate with sockets in said standard.

5. A dephlegmator, comprising a casing having a vapor inlet and a vapor outlet, a 75 plurality of partitions in said casing, means for adjustably supporting said partitions within said casing whereby the vertical positions of such partitions may be manually varied, said means including an adjustable element associated with each partition for 80 securing the partitions in adjusted positions.

6. A dephlegmator, comprising a casing, having a vapor inlet and a vapor outlet, a plurality of vertically spaced perforated plates mounted within said casing to obstruct the travel of vapors through the dephlegmator, manually adjustable means 85 associated with each plate for maintaining the plates in any desired vertical positions of adjustment relative to one another.

GUSTAV EGLOFF.
HARRY P. BENNER.
